CLAIM

The ornamental design for a speaker, as shown and described.

DESCRIPTION

FIG. 1 is an upper perspective view of the speaker showing my design.

FIG. 2 is a front elevation view thereof, showing speaker holes;

FIG. 3 is a back elevation view thereof;

FIG. 4 is a side elevation view thereof, an opposite side view being a mirror image thereof;

FIG. 5 is a top plan view thereof; and,

FIG. 6 is a bottom plan view thereof.

The broken lines shown are included for the purpose of illustrating portions of the speaker that form no part of the claim.

1 Claim, 2 Drawing Sheets(56)
